UNITED STATES PATENT OFFICE.

SAMUEL ABRAMSON, OF PHILADELPHIA, PENNSYLVANIA.

FIRE-ESCAPE.

1,216,041.

Specification of Letters Patent. Patented Feb. 13, 1917.

Original application filed June 8, 1916, Serial No. 102,411. Divided and this application filed August 5, 1916. Serial No. 113,248.

To all whom it may concern:

Be it known that I, SAMUEL ABRAMSON, a subject of the Czar of Russia, but who has declared his intention of becoming a citizen 5 of the United States, and now residing at the city of Philadelphia, in the county of Philadelphia and State of Pennsylvania, have invented certain new and useful Improvements in Fire-Escapes, of which the 10 following is a specification.

My present invention is a division of an application (Serial No. 102,411) filed by me under date of June 8th, 1916.

My present invention relates to a portable 15 fire-escape adapted to be slid along a wire or other type of rope and the descent controlled by friction exerted through a hand-grip of the said rope; and in such connection it relates to the particular structural arrangement 20 of the fire-escape for the defined purpose.

The nature, scope and characteristic features of my present invention will be more 25 fully understood from the following description taken in connection with the accompanying drawings forming part hereof, in which—

Figure 1 is an elevational view of the fire-escape of my invention illustrated in a condition 30 for use, with the body slip-loops with their take-up rings and showing also the suspended glove or mitt as part of the fire-escape friction controlling member to which glove or mitt the hand is fitted for gripping 35 the rope to regulate the rapidity of descent of the person suspended on the said rope.

Fig. 2 is a view partly in elevation and partly in section of the fire-escape, showing the internal arrangement of the same and 40 also how the rope circuitously courses there-through and the friction clutch member of the fire-escape for engaging the rope by a gloved manipulation of the rope to regulate descent; and

Fig. 3 is an end view of the said fire-escape.

Referring to the drawings *a*, is the device, 45 consisting of a metal casting of irregular shape in outline and as arranged reversible, as will be clearly understood from Fig. 2. In one portion are formed eyes *a*¹, for engaging body slip-loops *b*, having take-up

rings *b*¹ thereon. The loops span the body of the person so as to fit under the arm-pits of the person. To the right of the eyes *a*¹ 55 and forming part of the casting *a*, is arranged a curved formation *a*², having a grooved face for a rope *c*, to enter and travel therein and between upper and lower friction surfaces *a*³ and *a*⁴, as illustrated in Fig. 60 2. Opposite the curved formation *a*² of the fire-escape is pivoted a friction clutch member *a*⁵, with a depending stem *a*⁶, terminating in an eye *a*⁷, as clearly shown in Fig. 2. This eye *a*⁷, carries a strap *d*, to the lower 65 end of which is movably connected a glove or mitt *d*¹ of leather or other suitable material, for ready application to the hand for gripping the rope *c*, so as to control the amount of friction brought to bear instantly 70 between the clutch member *a*⁵, and the rope *c*, in its contact with the curved formation *a*², of the said device to thereby hasten or retard the descent of the suspended person *ad libitum* the rope *c*. 75

The arrangement of the fire-escape just described is such that it is reversible as will be apparent from Fig. 2 of the drawings and also that several persons can, with safety descend suspended therefrom at one 80 and the same time.

Having thus described the nature and object of my invention, what I claim as new and desire to secure by Letters Patent is:—

1. A fire-escape comprising a casting having 85 an internal curved formation for a rope to seat therein, and a pivotal clutch member arranged opposite said formation and carrying a suspended glove or mitt to permit of safely gripping said rope, substantially 90 as and for the purposes described.

2. A fire-escape, comprising a casting having 95 an internal curved formation for a rope to travel therein and a pivotal clutch member arranged opposite said formation and carrying an eye-bar over which said rope travels and said bar carrying a suspended glove or mitt to permit of the safe gripping of said rope, substantially as and for the purposes described. 100

3. A fire-escape, comprising a casting, having eyes for body slip-loops, a grooved formation arranged internally of said casting for a rope to engage and travel, friction

guide surfaces located above and below said formation for said rope to respectively engage, a clutch member pivoted to said casting and carrying a movable glove or mitt to permit of the safe gripping of said rope in descent, substantially as and for the purposes described.

Copies of this patent may be obtained for five cents each, by addressing the "Commissioner of Patents, Washington, D. C."

In witness whereof, I have hereunto set my signature in the presence of two subscribing witnesses.

SAMUEL ABRAMSON.
